UNITED STATES PATENT OFFICE.

MOSES M. MARCUSE, OF NEW YORK, N. Y.

DESIGN FOR A BOX.

No. 39,142.

Specification for Design.

Patented Feb. 18, 1908.

Application filed November 3, 1906. Serial No. 341,961. Term of patent 14 years.

To all whom it may concern:

Be it known that I, MOSES M. MARCUSE, a citizen of the United States, residing in the city, county, and State of New York, have invented a new, original, and ornamental Design for Boxes, of which the following is a specification.

The design in question is shown in perspective in the accompanying drawings.

My design covers a box or container particularly suited to bottles and having a body portion of rectangular cross section two of the faces of which incline together forming a

wedge-shaped top, while the other two faces fold inward to meet so as to form two opposite and symmetrically placed wedge-shaped hollows or spaces immediately beneath the meeting edges of the first named faces.

What I claim is—

The ornamental design for a box as shown and described.

MOSES M. MARCUSE.
